UNITED STATES PATENT OFFICE.

IRA V. HUMPHREY, OF HIGHLAND PARK, PENNSYLVANIA.

DESIGN FOR A TIRE.

55,048.

Specification for Design.

Patented May 4, 1920.

Application filed November 24, 1919. Serial No. 340,424. Term of patent 3½ years.

To all whom it may concern:

Be it known that I, IRA V. HUMPHREY, a citizen of the United States, residing in Highland Park, Delaware county, Pennsylvania, have invented a certain new, original, and ornamental Design for a Tire, of which the following is a specification, reference being had to the accompanying drawings, forming part thereof, in which—

Figure 1, is a plan view of a portion of the

tire forming the subject of my new, original and ornamental design.

Fig. 2, is a side elevation of a portion of the tire shown in Fig. 1, and

Fig. 3, is a cross sectional view of my new, original and ornamental design for a tire.

I claim:

The ornamental design for a tire, substantially as shown.

IRA V. HUMPHREY.
